(74) Attorney, Agent, or Firm—Nelson Mullins Riley & Scarborough, LLP

(57) **CLAIM**

The ornamental design of a stackable container, substantially as shown and described.

DESCRIPTION

FIG. 1 is a perspective view of a stackable container embodying the design of the present invention;

FIG. 2 is a perspective view of the stackable container illustrated in FIG. 1, the container being in the inverted position;

FIG. 3 is a front elevational view of the stackable container illustrated in FIG. 1, the rear view being a mirror image of the front view;

FIG. 4 is a right side elevational view of the stackable container illustrated in FIG. 1, the left side view being a mirror image of the right side view;

FIG. 5 is a top plan view of the stackable container illustrated in FIG. 1; and

FIG. 6 is a bottom view of the stackable container illustrated in FIG. 1; and,

FIG. 7 is a front elevational view of the stackable container illustrated in FIG. 1, in an arrangement of multiple stacked containers.

The broken lines in FIG. 7 are for illustrative purpose only and form no part of the claimed design.
